PAPER HOLDER

Filed March 26, 1927

UNITED STATES PATENT OFFICE

ARCHIBALD I. MCCOLL, OF KALAMAZOO, MICHIGAN

PAPER HOLDER

Application filed March 26, 1927. Serial No. 178,568.

My improved paper holder is especially designed for holding sheets or wrapping paper although desirable for use in holding sheets of any character which it is desired to support so that they may be readily withdrawn one by one.

The main objects of my invention are:

First, to provide an improved paper holder which provides an effective shipping pack-

age, effectively protecting the sheets.

Second, to provide an improved paper holder which supports the sheets so that they may be conveniently grasped and removed one at a time.

Objects relating to details and economies of construction and operation of my invention will definitely appear from the detailed description to follow.

The invention is defined and pointed out in the claims.

A structure which is a preferred embodiment of my invention is illustrated in the accompanying drawing, forming a part of this application, in which:

Fig. 1 is a perspective view of my improved paper holder or carton with a body of sheets therein adjusted for shipment or storage.

Fig. 2 is a vertical central section on a line corresponding to line 2-2 of Fig. 4.

Fig. 3 is a horizontal section on a line corresponding to line 3-3 of Figs. 2 and 4.

Fig. 4 is a rear elevational view.

Fig. 5 is a plan view of the carton blank.

Fig. 6 is a perspective view of the carton or holder blank with a body of sheets laid thereon partially folded.

In the drawing similar reference characters refer to similar parts throughout the several views.

Referring to the drawing, my improved carton or holder is formed of an integral blank, as illustrated, and comprises a rear wall 1, bottom wall 2, front wall 3, and a top wall 4, the top wall being narrower than the bottom wall so that its rear edge is spaced from the rear wall, as shown in Fig. 2.

The rear, bottom, front and top walls are formed as a continuous strip of uniform width.

The front wall 3 is extended at its ends

into end walls 5 which terminate in flaps 6 which are folded upon and secured to the rear wall as by means of adhesive strips 7 (see Fig. 4).

The bottom wall 2 has end flaps 8 which are turned upwardly and are embraced by the end walls, thereby closing the package at the bottom and also making a very secure or rigid structure.

The top wall is provided with an inwardly projecting flap-like extension 9 which engages within the fold or bight of a body of sheets, as 10, folded upon itself, with the inner ends of the sheets arranged between this extension 9 and the front wall, and the outer ends of the sheets projecting between the inner edge of the top and the rear wall, as shown in Fig. 2.

Owing to the folding of the sheets upon themselves their projecting ends are "fanned", as shown in Fig. 2, so that they may be conveniently grasped.

The extension 9 serves as a sheet holder and engages within the bights of the sheets so that they may be withdrawn one by one.

To further retain and support the sheets within the holder and to receive the pulling stress, I provide the rear wall with extensions 11 having sheet engaging flap portions 12 which are folded or engaged within the bight of the sheets whereby they are effectively retained in the holder and these sheet engaging members coacting with the sheet holding member 9 in supporting the sheets.

The rear wall 1 preferably extends above the top wall and is provided with an eyelet 13 from which it may be suspended. The back also has an extension flap 14 which may be folded over the projecting ends of the sheets, as shown in Fig. 1, thereby providing a suitable closure and protecting means for the ends of the sheets, this flap being engaged within the rear edge of the top 4, as shown in Fig. 1.

The holder may be placed wherever convenient, that is, it may be suspended or set upright or laid in various positions as may be convenient.

My present improvements are an adaptation of, and in some respects, an improvement

upon the structure shown in my application for Letters Patent filed October 3, 1925, Serial No. 60,192.

Having thus described my invention, what I claim as new and desire to secure by Letters Patent is:

1. A paper holder comprising rear, bottom, front, top and end walls, the rear and front walls being diverged downwardly, the end walls extending from the edges of said front wall and having securing flaps overlapping and secured to said rear wall, the bottom having flaps projecting upwardly within the end walls, the inner edge of said top wall being spaced from the rear wall and having an inwardly projecting flap at its inner edge adapted to engage within the fold of a body of sheets folded upon itself, the rear wall having sheet engaging members extending forwardly from its vertical edges and provided with inturned flaps disposed within the fold of a body of sheets.
2. A paper holder comprising rear, bottom, front, top and end walls, the rear and front walls being diverged downwardly, the inner edge of said top wall being spaced from the rear wall and having an inwardly projecting flap at its inner edge adapted to engage within the fold of a body of sheets folded upon itself, the rear wall having sheet engaging members extending forwardly from its vertical edges and provided with inturned flaps disposed within the fold of a body of sheets.
3. A paper holder comprising rear, bottom, front, top and end walls, the rear and front walls being diverged downwardly, the inner edge of said top wall being spaced from the rear wall and having an inwardly projecting flap at its inner edge adapted to engage within the fold of a body of sheets folded upon itself, the rear wall being extended above the top wall and having a flap at its upper edge adapted to be folded over the projecting ends of sheets and engaged within the rear edge of the top wall.
4. A paper holder comprising rear, bottom, front, top and end walls, the rear and front walls being diverged downwardly, the end walls extending from the edges of said front wall and having securing flaps engaging said rear wall, the bottom having flaps projecting upwardly within the end walls, the inner edge of said top wall being spaced from the rear wall, the rear wall having sheet engaging members extending forwardly from its vertical edges and provided with portions disposed within the fold of a body of sheets folded upon itself.
5. A paper holder comprising rear, bottom, front and top walls, the rear and front walls being diverged downwardly, the inner edge of said top wall being spaced from the rear wall, the rear wall having sheet engaging members extending forwardly from its ver-

tical edges and provided with portions disposed within the fold of a body of sheets folded upon itself, the rear wall being extended above the top wall and having a flap at its upper edge adapted to be folded over the projecting ends of sheets.

6. A paper holder comprising rear, bottom, front and top walls, the rear and front walls being diverged downwardly, the inner edge of said top wall being spaced from the rear wall and having a downwardly projecting sheet holder flap at its inner edge adapted to engage within the fold of a body of sheets folded upon itself, the rear wall having sheet engaging members extending forwardly from its vertical edges and provided with inturned portions disposed within the fold of a body of sheets.

7. A paper holder comprising rear, bottom, front and top walls, the rear and front walls being diverged downwardly, the inner edge of said top wall being spaced from the rear wall, the rear wall having sheet engaging members extending forwardly from its vertical edges and provided with portions disposed within the fold of a body of sheets folded upon itself.

In witness whereof I have hereunto set my hand.

ARCHIBALD I. McCOLL.
